UNITED STATES PATENT OFFICE.

WILLIAM S. LANEY, OF BALTIMORE, AND CHARLES F. YOST, OF CANAL
WINCHESTER, OHIO.

REIN-HOLDER.

SPECIFICATION forming part of Letters Patent No. 287,081, dated October 23, 1883.

Application filed March 27, 1883. (No model.)

To all whom it may concern:

Be it known that we, WILLIAM S. LANEY, residing at Baltimore, in the county of Fairfield and State of Ohio, and CHARLES F. YOST, residing at Canal Winchester, in the county of Franklin and State of Ohio, both citizens of the United States, have invented certain new and useful Improvements in Rein-Holders; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention has relation to rein-holders specially adapted to be secured to the dash-board of vehicles.

It consists in the combination of two arms having their adjacent ends hinged on suitable supports, and springs connecting the supports and the under sides of the said arms, and in other improvements, as will be hereinafter described, and pointed out in the claims.

In the drawings, Figure 1 is an elevation of a dash-board having our improvement attached. Fig. 2 is a top view of the holding-drums. Fig. 3 is a vertical section on line $x-x$, Fig. 1. Fig. 4 shows the under side of the holding-arms; and Fig. 5 is a top view, showing the holder in position on the dash-board, with a slight modification in the support, as will be described.

The supporting-base A is secured to the dash-board by means of screws $a-a'$, passed through a suitable plate on the outer side of the dash-board and into the base, as shown, so as to firmly secure the same in position. The base-piece is made triangular, and its sides are inclined downward from its apex, and extend laterally a sufficient distance to provide bearings for the outer end of the arms $c-c'$, hereinafter described. Flanges a^2 are extended up from the opposite side of the said base. These flanges may be extended entirely to the apex, or only along the portion where the rein is passed, the object being to provide a channel between them, whereby the reins will be more

securely held, as will be hereinafter described. From the apex of the triangular base-piece we project lugs a^3-a^3 , between which we extend the rod b , which furnishes a bearing for the arms $c-c'$. The inner ends of these arms $c-c'$ are hinged in suitable manner on the shaft. We prefer to construct them, as clearly shown in Figs. 2 and 4, with the jaws c' of the arm c extended forward on either side of the inner end of the arm c' , and with the inner end of the said arm c' beveled, so it will extend under the adjacent end of the arm c , which is beveled to receive it, thus forming a close neat joint. These arms, however, it will be understood, could be hinged in any suitable manner on the rod b , or otherwise, as desired; but we prefer that shown, as a close neat joint is thereby provided. The adjacent ends of these arms being hinged on the rod b , extended between the lugs a^3 , above the upper part of the base A, a space, d , is provided to receive the reins, when the latter are slipped under the outer ends of the arms. These arms extend outward between the jaws a^3-a^3 , and are brought down to and rested against the base A, at a suitable distance from the inner ends to provide the space d , wide enough to receive the reins, and their outer ends are turned up, so that the reins may be slipped readily under them when so desired. The spring e is coiled around the rod b , and its opposite ends are extended and made fast to the under sides of the arms $c-c'$, so that the outer ends of said arms will be held against the supporting-base in the channel formed between the side flanges, a^2 , as shown in Figs. 3 and 5, and secure the reins when slipped under the said arms and into the space d . The ends of this spring e may be secured to the under side of said arms by passing its end over a wire or rod, c^2 , as shown in Fig. 4; or the arms $c-c'$ might be cast or otherwise formed with sockets to receive the end of the spring e , as shown at c^3 , Fig. 3. In order to conceal the spring e , and also to protect the same from the weather, we dish the under side of the inner ends of the arms, so that the spring will be retained wholly within the mortises thus formed, as shown.

Instead of employing the base A, extend-

ing laterally, as shown in Figs. 1 and 3, where so desired, the outer ends of this base might be cut away, leaving the central supports, as shown in Fig. 5, which could be suitably secured to the dash-board, and the arms *c c'* could be hinged thereon, and springs *ff* could also be arranged to connect the said supports and under side of the arms *c c'*. In this case the outer ends of the arms *c c'* would bear directly against the dash-board. We prefer, however, the use of the base *A*, extended laterally so as to provide a bearing for the outer ends of the arms *c c'*, as thereby the ends of said arms are held up above the dash-board, and the reins may be more readily slipped thereunder. We also prefer to provide the base *A* with the side flanges, *a² a²*, as the under side of the arms *c c'* extend below the top of the said flanges, and the reins, when passed under the outer ends of said arms, will be depressed within the channel formed between the said flanges, and will be more securely held in place than when these flanges are not used. By the grip thus provided the rein may be held taut, instead of being allowed to hang loosely, as in rein-holders of ordinary construction.

In operation it will be understood the reins are slipped under the outer ends of the arms

c c', where they will be held by the mechanism before described.

Having thus described our invention, what we claim, and desire to secure by Letters Patent, is—

1. In a rein-holder, the arms *c c'* and the spring *e*, said arms being provided with recesses on their undersides, whereby said spring is secreted from view and liability to contact with the reins, in combination with the base *A* and pivot-rod *b*, the spring being coiled around said rod, substantially as described, and for the purposes set forth.

2. The rein-holder, substantially as described and shown, consisting of the base *A*, having side flanges, *a²*, and lugs *a¹*, projected from its apex, the rod *b*, the arms *c c'*, having their adjacent ends secured thereon, and the spring *e*, coiled around rod *b*, and having its opposite ends secured to the under side of the arms *c c'*, all as and for the purposes specified.

In testimony whereof we affix our signatures in presence of two witnesses.

WILLIAM S. LANEY.

CHARLES F. YOST.
